UNITED STATES PATENT OFFICE.

DONALD BARNS MORISON, OF HARTLEPOOL, ENGLAND.

STEAM-CONDENSING PLANT.

1,246,771.

Specification of Letters Patent. Patented Nov. 13, 1917.

Application filed April 6, 1916. Serial No. 89,459.

To all whom it may concern:

Be it known that I, DONALD BARNS MORISON, a subject of the King of Great Britain and Ireland, residing at Hartlepool, in the county of Durham, England, have invented the Improvements in or Relating to Steam-Condensing Plants, of which the following is a specification.

It is known to withdraw aerated vapor from a condenser by apparatus comprising steam ejectors arranged in series the air being discharged to the atmosphere with or without an additional air expelling device, and my invention relates to apparatus of this kind.

In the working of condensing steam engines, the total quantity of air which mixes with the steam and has to be discharged from the condenser to the atmosphere by an air pump, consists of the quantity of air which enters the boiler with a unit volume of feed water and the quantity of air which leaks into the vacuum system through defective joints and connections. The latter quantity is variable as it depends on the air tightness of the plant at any given moment.

When aerated exhaust steam enters a condenser and the design of the condenser is normal, that is, one in which the proportion of air, contained in a unit volume of the mixture of steam and air, gradually increases from the point of entry to the condenser to the point of withdrawal from the condenser, it follows that the greater the volume of aerated vapor withdrawn from the condenser by the air withdrawing apparatus per unit of time, the smaller will be the proportion of air in the total volume of steam and air which remains in the condenser at any given moment, and therefore the greater will be the quantity of heat that can be transmitted from the exhaust steam to the condensing water, with the result that the temperature of the vapor contents of the condenser is lowered and the vacuum corresponding thereto is raised.

The volume of aerated vapor that can be economically withdrawn from a condenser is governed by the value of the steam used by the air withdrawing apparatus.

The object of this invention is, over a predetermined range of air entry into the vacuum system, to withdraw from a condenser under vacuum, with the expenditure of a given quantity of steam, a larger volume of aerated vapor (and to discharge the

air contained in such volume to the atmosphere), than has hitherto been obtainable with apparatus of the kind referred to.

When air as contained in aerated vapor is withdrawn from a condensing vessel by a steam ejector which discharges the air direct to the atmosphere, I have found by experiment that the expenditure of steam required for the discharge of a given quantity of air becomes uneconomical when the vacuum exceeds 27 inches of mercury. I have also found that for such an ejector the steam required economically to discharge air to the atmosphere must be high pressure steam, so that the economical use of such steam becomes of very great importance in air discharging apparatus.

According to my invention I withdraw the aerated vapor from the condenser by the action of three or more ejectors arranged and proportioned in series in accordance with the principles hereinafter set forth. The first of these ejectors (hereinafter called the air withdrawing ejector) which withdraws direct from the condenser, I arrange and proportion in such manner that it works between a small pressure difference of suction and discharge and is therefore capable of withdrawing a large volume of aerated vapor over a predetermined range of air entry into the vacuum system, with an economical expenditure of steam. The pressure difference is so small (in the case of a normally air tight system it would usually not exceed 1.5 pounds per square inch) that under the conditions of working, the ejector is enabled to withdraw the maximum volume obtainable with an economical expenditure of steam. I discharge to the atmosphere, usually through a suitable condensing device, the air contained in the withdrawn aerated vapor by another steam ejector (hereinafter called the air delivery ejector) designed to operate with an economical expenditure of high pressure steam. This ejector should work between such pressure differences that the degree of compression is by preference the maximum I can get by an economical expenditure of high pressure steam for a given quantity of air. I find that a good pressure difference in the case of a normally air tight system is about 12 pounds per square inch, but any pressure difference from about 9 pounds to 13.5 pounds would be within the scope of my invention. I am enabled to design and oper-

- ate these ejectors in the above manner by placing between them another steam ejector (hereinafter called the controlling ejector) which is so designed that it will maintain on the discharge side of the air withdrawing ejector a pressure which bridges the gap between the discharge pressure of the air withdrawing ejector and the suction pressure necessary for the air delivery ejector.
- 10 The degree of compression by the controlling ejector when so used is well within its economical range, and therefore the steam used by it is not only economical in quantity but may be low pressure steam and therefore of low power producing value.

In apparatus according to my invention, because each of the three ejectors is arranged so as to work at their respective ranges of economical pressure differences, the total expenditure of steam required in order to produce the necessary pressure differences and the resulting beneficial effects is well within the range of the requirements of steam engineering practice, a result which has not heretofore been obtained with apparatus of the kind referred to.

By way of example I will describe, with reference to the accompanying diagrammatic drawings, two forms of apparatus constructed and operating in accordance with my invention, and in which the ejectors are provided with intermediate condensers in a known manner. Figure 1 shows three ejectors arranged in series. Fig. 2 shows diagrammatically the results obtained by apparatus designed and constructed and operating in accordance with my invention, arranged substantially as illustrated in Fig. 1, and tested in the usual manner. Fig. 3 illustrates a modification of Fig. 1, and in which four ejectors are employed.

With reference to Fig. 1. The apparatus comprises three steam operated ejectors arranged in series, namely, an air withdrawing ejector *a*, a controlling ejector *b*, and an air delivering ejector *c*. The ejector *a* withdraws aerated vapor from the main condenser *d* and discharges into the condensing receiver *e*; the ejector *b* withdraws aerated vapor from the condensing receiver *e* and discharges into the condensing receiver *f*; the ejector *c* withdraws from the condensing receiver *f* and discharges into the water operated ejector condenser *n*, condensate or other water being delivered through the branch *p* at such a velocity as will prevent any back pressure greater than atmospheric, or if desirable to create a vacuum, on the discharge side of the ejector *a*.

60 In the apparatus tested, the steam supplied to the ejectors *a* and *b* was of low pressure, and that supplied to the ejector *c* was of high pressure. The quantity of water circulated from the tank *t* through the closed vessel (condenser *d*) and back into

the tank *t* was 75,000 pounds per hour. The water was withdrawn from the closed vessel by a pump and flowed back to the closed vessel under atmospheric pressure. The temperature of the water was maintained at 70-80 degrees Fahrenheit, which is the boiling temperature of water under 28.97 inches vacuum.

In a plant condensing 75,000 pounds of steam per hour, the quantity of free air normally discharged from the system, as from the tank *t*, assuming the plant to be exceptionally air tight in its pipes and connections, would be approximately 4 cubic feet per minute; but as insidious is air leakage and so highly detrimental to the efficiency of a steam turbine is a fall in vacuum, that it is often desired to provide air withdrawing apparatus which can maintain the normal vacuum under a condition of air leakage which represents from 2 to 3 times the quantity withdrawn by the apparatus under a condition of exceptional air tightness of joints and connections. It will be seen by referring to the diagram Fig. 3 that when air was admitted to the closed vessel (condenser *d*) at a rate of 8 cubic feet per minute, the vacuum was 28.9 inches. With double this air admission, that is, 6 cubic feet per minute, a vacuum of 28.8 inches was maintained; while with three times the above air admission, namely 8 cubic feet per minute, the vacuum only fell to 28.7 inches.

The diameters of the steam jet nozzles in the ejectors *a*, *b*, *c* were respectively 0.5 inches, 0.5 inches and 0.218 inches, the average steam pressures being about 7, 16 and 115 pounds per square inch respectively. The cross sectional areas of the combining tubes are designed of such proportions that (when operating collectively) velocities are produced which enable the general effect described to be obtained, and in this particular example the relative areas of the combining tubes *l*, *h*, *g* were respectively, for the delivery ejector, 1; for the control ejector, 5.6; and for the withdrawing ejector, 10.7. The mean compression pressures over the total range of air entry were about 0.5 pounds for ejector *a*, 2 pounds for ejector *b*, and 11.7 pounds for ejector *c*.

The small pressure difference maintained between the suction and discharge sides of the ejector *a*, namely, 0.5 pounds per square inch, enabled the large volume of aerated vapor to be economically withdrawn from the closed vessel (under the conditions set forth) which was necessary in order to produce the results shown on the diagram.

The mean degree of compression produced by the steam ejector *c* when expelling the air to the atmosphere against the pressure difference between its suction and discharge sides, namely, about 11.7 pounds per square inch, was such that the ejector *c* operated

with an economical expenditure of steam. In order to support or sustain the respective performances of ejectors *a* and *c*, there is placed between them the ejector *b*. The pressure difference to be maintained by the ejector *b* in order to complete the absolute pressure due to 28.9 inches vacuum, namely, 14.2 pounds, is in this particular case about 2 pounds and the degree of compression by 10 the ejector *b* under these conditions is so well within its economical range that the expenditure of steam therein is economical, and moreover the steam may be of low pressure. These proportions and steam pressures were those adopted and the results 15 were those obtained in connection with this particular test under the conditions set forth, but it is to be understood that in all cases the proportions of the ejector and the 20 steam pressures employed depend on the particular conditions associated with any particular plant. For example in a submarine warship the essentials in a condensing plant are minimum weight and minimum space occupied. In such a case the 25 predetermined range of air entry may be an irreducible minimum with no provision for accidental air leakage while the steam pressures under which the ejectors operate 30 would be consistent with the weight and space requirements of the plant, whereas in an electric power station on land where economy of production of electric current is a first essential the condensing plant would 35 be more liberally proportioned, the margin for accidental air leakage would be large and the pressures of steam supply to the 40 ejectors would be consistent with obtaining the desired results at a minimum cost in steam.

Fig. 2 is a modification of Fig. 1, the similar parts being denoted by the same letters of reference. In Fig. 1, I have described apparatus in which only one controlling ejector is employed, but I may when 45 circumstances warrant it—as for example when a considerable quantity of low pressure steam is available as from a closed exhaust system—employ more than one controlling ejector, and Fig. 2 shows two controlling ejectors *b* and *b'* arranged in series with the ejectors *a* and *c* and intermediate condensers *e*, *f* and *f'*. In this example the final ejector *c* is shown discharging into a 50 nozzle submerged in water contained in the tank *t*.

The water is discharged from the condensing receivers when such are employed by any known or suitable apparatus. The 55 steam operated ejectors may be of any known type, and the condensing receivers when employed may be of the direct contact or the surface contact type; and any portion of the water supply may be artificially cooled.

Although I have described the invention with reference to steam condensers, it is to be understood that the invention can be employed for the removal of large volumes of gases from other vessels under vacua, 70 such for example as in the case of the manufacture of sugar.

I claim:

1. Apparatus comprising a number of steam operated ejectors (exceeding two) arranged in series for withdrawing from a low pressure and discharging to a higher pressure, said ejectors being so constructed that the degree of compression in each successive stage of compression, from the lower 80 to the higher pressure, is greater than in the preceding stage.

2. Apparatus comprising a number of steam operated ejectors (exceeding two) arranged in series with intermediate condensers, said ejectors being so constructed that the degree of compression in each successive stage of compression, from the lower to the higher pressure, is greater than in the preceding stage.

3. Apparatus comprising a number of steam operated ejectors (exceeding two) arranged in series with intermediate condensers, said ejectors being so constructed that the degree of compression in each successive stage of compression, from the lower to the higher pressure, is greater than in the preceding stage, and a water operated ejector condenser into which the last steam 95 ejector discharges.

4. Apparatus for withdrawing from a low pressure and discharging to a higher pressure, comprising an air withdrawing ejector, a controlling ejector and an air delivering ejector, said ejectors being arranged in series in the order mentioned and constructed in such a manner that the air withdrawing ejector works under a small pressure difference, the air delivery ejector works under a pressure difference which is at or 100 near to the maximum pressure difference economically attainable, and the controlling ejector produces the degree of compression necessary to cover the gap between the discharge pressure of said air withdrawing 110 ejector and the pressure at the suction side of said air delivery ejector.

5. Apparatus for withdrawing from a low pressure and discharging to a higher pressure, comprising an air withdrawing 120 ejector, controlling ejectors and an air delivery ejector, said ejectors being arranged in series in the order mentioned and constructed in such a manner that the air withdrawing ejector works between a small pressure difference, the air delivery ejector works under a large pressure difference, and the controlling ejectors produce the degree of compression necessary to cover the gap between the discharge pressure of said air 130

withdrawing ejector and the pressure at the suction side of said air delivery ejector.

6. Apparatus for withdrawing from a low pressure and discharging to a higher pressure comprising the following devices arranged in series in the order mentioned, an air withdrawing ejector, a condensing receiver, a controlling ejector, another condensing receiver, and an air delivery ejector, 10 said ejectors being constructed in such a manner that the air withdrawing ejector works under a small pressure difference, the air delivery ejector works under a large pressure difference, and the controlling ejector produces the degree of compression necessary to cover the gap between the discharge pressure of said air withdrawing ejector and the pressure at the suction side of said air delivery ejector.

20 7. Apparatus for withdrawing from a low pressure and discharging to a higher pressure, comprising the following devices arranged in series in the order mentioned, an air withdrawing steam ejector, a condensing receiver, a controlling steam ejector, another condensing receiver, an air delivery steam ejector, and a water operated ejector condenser, said steam ejectors being constructed in such a manner that the air withdrawing 25 ejector works under a small pressure difference, the air delivery ejector works under a large pressure difference, and the controlling ejector produces the degree of compression necessary to cover the gap between the discharge pressure of said air withdrawing 30 ejector and the pressure at the suction side of said air delivery ejector.

8. Apparatus for the removal of air from steam condensers comprising the following 40 devices arranged in series in the order mentioned, an air withdrawing steam ejector, a condensing receiver, a controlling steam ejector, another condensing receiver, an air delivery steam ejector, and a steam condensing device, said steam ejectors being constructed in such a manner that the air withdrawing 45 ejector works under a pressure difference not exceeding 1.5 pounds per square inch, the air delivery ejector works under a 50 pressure difference which is not greater than 13.5 pounds per square inch nor less than 9 pounds per square inch, and the controlling ejector produces the degree of compression necessary to cover the gap between the discharge 55 pressure of said air withdrawing ejector and the pressure at the suction side of said air delivery ejector.

9. In apparatus comprising a number of steam operated ejectors (exceeding two) arranged in series for withdrawing from a low pressure and discharging to a higher pressure, constructing said ejectors so that the degree of compression in each successive stage of compression, from the lower to the 60 higher pressure, is greater than in the pre- 65

ceding stage, the ejector which withdraws from the lowest pressure working under a small pressure difference, the ejector which delivers to the highest pressure working by preference under the maximum pressure difference economically attainable, and the intermediate ejector producing the degree of compression necessary to cover the pressure gap between the first and last ejectors.

10. Apparatus for withdrawing from a 75 low pressure and discharging to a higher pressure, comprising an air withdrawing ejector, a controlling ejector and an air delivering ejector, said ejectors being arranged in series in the order mentioned and constructed in such a manner that the air withdrawing ejector works under a small pressure difference, the air delivery ejector works under a large pressure difference, and the controlling ejector produces the degree of compression necessary to cover the gap between the discharge pressure of said air withdrawing ejector and the pressure at the suction side of said air delivery ejector, the nozzles of said air withdrawing and controlling ejectors being supplied with low pressure steam and the nozzle of said air delivery ejector being supplied with high pressure steam.

11. Apparatus comprising a number of 95 steam operated ejectors (exceeding two) arranged in series for withdrawing from a low pressure and discharging to a higher pressure, in which the ejector which withdraws from the lowest pressure works under a 100 pressure difference not exceeding 1.5 pounds per square inch.

12. Apparatus comprising a number of 105 steam operated ejectors (exceeding two) arranged in series for withdrawing from a low pressure and discharging to a higher pressure, in which the ejector which discharges to the highest pressure works under a pressure difference which is not greater than 13.5 pounds per square inch nor less than 9 pounds per square inch.

13. Apparatus comprising a number of 115 steam operated ejectors (exceeding two) arranged in series for withdrawing from a low pressure and discharging to a higher pressure, in which the ejector which withdraws from the lowest pressure works under a pressure difference not exceeding 1.5 pounds per square inch, and the ejector which discharges to the highest pressure works under a pressure difference which is not greater than 13.5 pounds per square inch nor less than 9 pounds per square inch.

14. Apparatus comprising three steam operated ejectors arranged in series for withdrawing from a low pressure and discharging to a higher pressure, the first ejector which withdraws from the lowest pressure normally producing a pressure difference of approximately 0.5 pounds per square 125 130

inch, the third ejector which discharges to the highest pressure normally producing a pressure difference of approximately 12 pounds per square inch, and the second or 5 intermediate ejector normally producing the remaining pressure difference between the first and third ejectors, namely, approximately 2 pounds per square inch.

15. Apparatus for the removal of air from 10 steam condensers, comprising three steam operated ejectors arranged in series with intermediate condensers and a final water operated jet ejector condenser, the first steam ejector which withdraws from the condenser 15 normally producing a pressure difference of approximately 0.5 pound per square inch, the third steam ejector which discharges into the water operated ejector normally producing a pressure difference of 20 approximately 12 pounds per square inch, and the second steam ejector producing the remaining pressure difference between the first and third steam ejectors, namely, approximately 2 pounds per square inch.

16. In apparatus for the removal of air 25 from steam condensers, comprising three steam operated ejectors arranged in series with intermediate condensers, constructing the first ejector which withdraws from the lowest absolute pressure so that it performs 30 its predetermined amount of compressive work by the expenditure of an economical quantity of low pressure steam, constructing the third ejector which discharges to the highest pressure so that it performs its pre- 35 determined amount of compressive work by the expenditure of an economical quantity of high pressure steam, and constructing the second or intermediate ejector for low pressure steam so that an economical expenditure of steam of given power producing 40 value can be attained by the apparatus.

Signed at London this twenty second day of March 1916.

DONALD BARNS MORISON.
